VACUUM CLEANER CLEANING ATTACHMENT OR THE LIKE

George H. Frost, Ashland, Ohio, assignor to Westinghouse Electric Corporation, Pittsburgh, Pa., a corporation of Pennsylvania

Filed Aug. 20, 1965, Ser. No. 86,665

Term of patent 14 years

(Cl. D9—2)

FIG. 1.

FIG. 2.

FIG. 3.

FIG. 5.

FIGURE 1 is a top plan view of a vacuum cleaner cleaning attachment embodying my new design;

FIG. 2 is a front elevational view of the cleaning attachment shown in FIG. 1;

FIG. 3 is a side elevational view of the cleaning attachment shown in FIG. 1;

FIG. 4 is a bottom plan view of the cleaning attachment shown in FIG. 1; and

FIG. 5 is a rear elevational view of the cleaning attachment shown in FIG. 1.

The side elevational view not shown is identical to the side elevational view shown in FIG. 3.

The dominant features of my design reside in the portions shown in full lines.

This application is a continuation-in-part of my co-pending application, Serial No. 79,196, filed March 25, 1964, now abandoned.

I claim:

The ornamental design for a vacuum cleaner cleaning attachment or the like, as shown and described.
